UNITED STATES PATENT OFFICE.

CHARLES H. GURNEY, OF CHICAGO, ILLINOIS, ASSIGNOR TO THE CAPITAL MANUFACTURING COMPANY, OF SAME PLACE.

DESIGN FOR A HANDLE FOR PULLING TRAPS.

SPECIFICATION forming part of Design No. 19,980, dated July 1, 1890.

Application filed May 21, 1890. Serial No. 352,664. Term of patent 14 years.

To all whom it may concern:

Be it known that I, CHARLES H. GURNEY, a citizen of the United States, residing at Chicago, in the county of Cook and State of Illinois, have invented and produced a new and original Design for Handles, of which the following is a specification.

The object of this design is to provide a novel and ornamental handle for pulling traps; and the leading features thereof reside in a looped handle-rod, which is obovate in outline and terminates in a conical duplex spiral shank, one spiral part of which extends beyond the other spiral part in the form of a ring.

In the accompanying drawing, illustrating my design, the figure is a plan view of the handle.

In the drawing, the numeral 1 indicates the looped handle-rod, which is obovate in outline and terminates in a conical duplex spiral-shank 2 and 3, one spiral part of which projects beyond the other spiral part in the form of the ring 4, the whole presenting an ornamental and distinguishing appearance. 25

What I claim is—

The design for a handle, substantially as shown and described.

In testimony whereof I have affixed my signature in presence of two witnesses.

CHARLES H. GURNEY.
